(57) **CLAIM**

The ornamental design for a power and data connector, as shown and described.

DESCRIPTION

FIG. 1 is a perspective view of a power and data connector according to a first embodiment of our design;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top elevation view thereof;

FIG. 7 is a bottom elevation view thereof;

FIG. 8 is a perspective view of a power and data connector according to a second embodiment of our design;

FIG. 9 is a front elevation view thereof;

FIG. 10 is a back elevation view thereof;

FIG. 11 is a left side elevation view thereof;

FIG. 12 is a right side elevation view thereof;

FIG. 13 is a top elevation view thereof;

FIG. 14 is a bottom elevation view thereof;

FIG. 15 is a perspective view of a power and data connector according to a third embodiment of our design;

FIG. 16 is a front elevation view thereof;

FIG. 17 is a back elevation view thereof;

FIG. 18 is a left side elevation view thereof;

FIG. 19 is a right side elevation view thereof;

FIG. 20 is a top elevation view thereof;

FIG. 21 is a bottom elevation view thereof;

FIG. 22 is a perspective view of a power and data connector according to a fourth embodiment of our design;

FIG. 23 is a front elevation view thereof;

FIG. 24 is a back elevation view thereof;

FIG. 25 is a left side elevation view thereof;

FIG. 26 is a right side elevation view thereof;

FIG. 27 is a top elevation view thereof;

FIG. 28 is a bottom elevation view thereof;

FIG. 29 is a perspective view of a power and data connector according to a fifth embodiment of our design;

FIG. 30 is a front elevation view thereof;

FIG. 31 is a back elevation view thereof;

FIG. 32 is a left side elevation view thereof;

FIG. 33 is a right side elevation view thereof;

(Continued)

FIG. 34 is a top elevation view thereof;
 FIG. 35 is a bottom elevation view thereof;
 FIG. 36 is a perspective view of a power and data connector according to a sixth embodiment of our design;
 FIG. 37 is a front elevation view thereof;
 FIG. 38 is a back elevation view thereof;
 FIG. 39 is a left side elevation view thereof;
 FIG. 40 is a right side elevation view thereof;
 FIG. 41 is a top elevation view thereof; and,
